BEVERAGE VENDOR

Clare E. Hodgman, Mamaroneck, N.Y., assignor to The Coca-Cola Company, Atlanta, Ga., a corporation of Delaware

Filed Sept. 16, 1959, Ser. No. 57,573

Term of patent 14 years

(Cl. D52—3)

The opposite side of the vending machine is substantially the same in appearance as the side shown and the rear is unadorned.

The figures are lined to indicate contrast in color.

I claim:

The ornamental design for a beverage vendor, as shown and described.
